UNITED STATES PATENT OFFICE.

JOSEPH FIRNER, OF PRESCOTT, WISCONSIN.

WINDOW FRAME AND SASH.

1,330,034.

Specification of Letters Patent.

Patented Feb. 3, 1920.

Application filed June 28, 1919. Serial No. 807,824.

To all whom it may concern:

Be it known that I, JOSEPH FIRNER, a citizen of the United States, residing at Prescott, in the county of Pierce and State of Wisconsin, have invented certain new and useful Improvements in Window Frames and Sashes; and I do hereby declare the following to be a full, clear, and exact description of the invention, such as will enable others skilled in the art to which it appertains to make and use the same.

My present invention has for its object to provide an improved window frame and sash; and, to this end, it consists of the novel devices and combinations of devices herein-after described and defined in the claims.

In the accompanying drawings, which illustrate the invention, like characters indicate like parts throughout the several views.

20 Referring to the drawings:

Figure 1 is a fragmentary elevation of a window frame having mounted therein upper and lower window sashes in which the invention is embodied;

25 Fig. 2 is a vertical section taken substantially on the lines 2—2 of Figs. 1 and 3;

Fig. 3 is a fragmentary perspective view with some parts sectioned on the line 3—3 of Fig. 2;

30 Fig. 4 is a fragmentary elevation of the upper end of the lower sash, as adjusted in Fig. 2, together with the adjoining portion of the window frame;

Fig. 5 is a detail view in section taken on the line 5—5 of Fig. 2;

35 Fig. 6 is a detail view in section taken on the line 6—6 of Fig. 2;

Fig. 7 is a fragmentary perspective view with some parts sectioned on the line 7—7 of Fig. 2;

40 Fig. 8 is a view corresponding to Fig. 3, but showing a slight modification; and

Fig. 9 is a view corresponding to Figs. 3 and 8, but showing a still further modification.

45 Referring first to the construction shown in Figs. 1 to 7, inclusive, the numeral 10 indicates a window frame and the numeral 11 upper and lower window sashes therefor. Formed in the sides of the window frame 10 in the plane of each sash 11, is a pair of vertical channels 12. Covering each channel 12, is a vertical guide plate 13 secured to the respective side of the window frame 10 by screws 14 and having a longitudinal slot 15. It is important to note that the slots 15 are

considerably narrower than the channels 12 and are located equi-distant from the sides thereof. The inner longitudinal edge of each guide plate 13 is folded upon itself to afford a flange 16 that is laterally spaced from said guide plate to afford a channel 17.

The outer edge of each stile of each window sash 11 has formed therein a channel 18 in which is mounted a U-shaped rail 19, the flanges of which extend toward the inner faces of the window stiles. The inner flanges of the rails 19 rest upon the bottoms of the channels 18 and are secured to the window sashes by screws 20. It will be noted that the free longitudinal edges of the outer flanges of the rails 19 are spaced apart from the respective sides of the channels 18 to afford clearance, for a purpose that will presently appear.

Each window sash 11 is mounted between a pair of auxiliary sash stiles 21, in the form of flat bars which extend parallel to the guide plates 13, and are connected thereto at their upper ends, for sliding and pivotal movement, by screw-threaded studs 22, which loosely extend through apertures in said auxiliary sash stiles and through the slots 15. On the inner ends of the screw-threaded studs 22, are nuts 23 mounted in the channels 12, with freedom for vertical sliding movement; but held by the walls thereof against turning movement. Formed with the heads of the screw-threaded studs 22, are crank arms 24, which extend horizontally inward for vertical oscillatory movement parallel to and in close engagement with the outer faces of the flanges 16. By reference to Fig. 3, it will be noted that the inner vertical edge portions of the auxiliary sash stiles 21 are arranged to fold into the channels 17 and, together with the flanges 16, afford coöperating weather strips which close the joints between the auxiliary sash stiles and window frame, when the window sashes 11 are closed.

The outer vertical edge portions of the auxiliary sash stiles 21 are folded upon themselves to afford flanges 25 that project in the planes of the flanges 16 and are laterally spaced from said auxiliary stiles to afford channels 26. These flanges 25 are, in turn, folded outward upon themselves to afford rails 27, which interlock with the rails 19, as best shown in Fig. 6, and thereby connect the window sashes 11 to the auxiliary sash stiles 21 for longitudinal sliding

movement thereon. Obviously, the interlocking rails 19 and 27 also afford coöperating weather strips which close the joints between the window sashes 11 and the auxiliary sash stiles 21. Each pair of auxiliary sash stiles 21 is intermediately connected to the window frame 10 by a pair of vertically disposed links 28, having their upper ends pivoted at 29 to the inner faces of the flanges 25, and having their lower ends pivotally connected at 30 to the inner faces of the flanges 16 and at the lower ends thereof. When the window sashes 11 are closed, the links 28 fold within the channels 17 and 26. In the drawings, the window sashes 11 are arranged to swing outward on the links 28, and, during this movement of the window sashes, the lock studs 22, which act as pivots therefor, slide downward in the slots 15. To hold the window sashes 11 in open positions, the arms 24 are operated to turn the lock studs 22 in the held nuts 23, and thereby draw their heads and said nuts toward each other, and thereby frictionally clamp the auxiliary sash stiles 21 onto the guide plates 13.

To support the window sashes 11 from the auxiliary sash stiles 21, the upper ends of the channels 18 are terminated short of the upper end of said window sashes to afford stop shoulders 31, which engage the upper ends of the rails 27, and support said sashes therefrom. These shoulders 31 are preferably covered by a metal plate 32. The channels 18 extend completely through the lower ends of the window sash stiles 21 to permit the window sashes 11 to be separated therefrom, when swung open, as shown by full lines in Fig. 2, by drawing the window sashes from between the pivoted ends of said auxiliary sash stiles, as shown by broken lines in Fig. 2.

The construction shown in Fig. 8 is substantially identical with that shown in the figures just described, with the exception that in place of cutting or forming the slots 15 in the guide plates 13, said guide plates are folded to form channels 33 which closely follow the contour of the channels 12 and 50 said guide plates are contracted at the tops of their channels 33 to afford slots 34. In this construction, the nuts for the lock studs 22 are annular and have formed thereon ribs 35, slidably mounted in the slots 34, and 55 thereby hold said nuts against rotation.

In the construction shown in Fig. 9, the guide plates 13 have one of their longitudinal edge portions folded thereupon to afford channels 36, the bottoms of which extend into channels 37 formed in the sides of the window frame 10. The auxiliary sash stiles 21 are pivotally and slidably connected to the guide plates 13 by horizontally disposed arms 38 pivoted at 39 to said auxiliary sash stiles and have on their ends

heads 40 slidably mounted in the channels 36. The flanges 25 of the auxiliary sash stiles are of substantially the same width as the outer faces of the stiles of the window sashes 11 and are bent to form longitudinally extended ribs 41, which extend into channels 42 formed in the outer edges of the stiles of the window sashes 11, and slidably connect the window sashes to said auxiliary sash stiles. 75

From the above description, it is evident that the window sashes may be swung open to any desired extent and when open, the outer faces of the window sashes may be easily washed or the frames thereof painted. 80 Or, the window sashes, when open, may be readily detached from the auxiliary sash stiles by drawing the same inward, as shown by broken lines in Fig. 2, and washed, painted or repaired. 85

What I claim is:—

1. The combination with a window frame, of a pair of auxiliary sash stiles attached to the window frame for compound sliding and pivotal movement, and a window sash carried by the auxiliary sash stiles with freedom for longitudinal sliding movement thereon. 90

2. The combination with a window frame, of a pair of auxiliary stiles attached to the window frame for compound sliding and pivotal movement, a link intermediately and pivotally connecting one of the auxiliary sash stiles to the window frame, and a window sash carried by the auxiliary sash stiles with freedom for longitudinal sliding movement thereon. 95

3. The combination with a window frame, of a pair of auxiliary stiles attached to the window frame for compound sliding and pivotal movement, a link intermediately and pivotally connecting one of the auxiliary sash stiles to the window frame, a window sash carried by the auxiliary sash stiles with freedom for longitudinal sliding movement thereon, and a lock for securing one of the auxiliary sash stiles against sliding movement on the window frame. 105

4. The combination with a window frame, of a pair of auxiliary sash stiles attached to the window frame for compound sliding and pivotal movement, a window sash, and co-operating interlocking rails longitudinally slidably connecting the window sash to the auxiliary sash stiles. 115

5. The combination with a window frame, of a pair of auxiliary sash stiles attached to the window frame for compound sliding and pivotal movement, a window sash longitudinal slidably mounted on the auxiliary sash stiles, and stops limiting the downward sliding movement of the window sash on the auxiliary sash stiles. 125

6. The combination with a window frame, of a pair of auxiliary sash stiles attached 130

to the window frame for compound sliding and pivotal movement, a window sash slidably mounted on the auxiliary sash stiles with freedom for separation therefrom by 5 an upward longitudinal movement, and stops limiting the downward sliding movement of the window sash on the auxiliary sash stiles.

7. The combination with a window frame, 10 of a pair of auxiliary sash stiles attached to the window frame for compound sliding and pivotal movement, a window sash carried by

the auxiliary sash stiles with freedom for longitudinal sliding movement thereon, and weather strips on the window frame with 15 which the auxiliary sash stiles interlock when moved into a position to close the window sash.

In testimony whereof I affix my signature in presence of two witnesses.

JOSEPH FIRNER.
